[57] CLAIM

The ornamental design for a divider of razor blade cartridge dispenser, as shown and described.

DESCRIPTION

FIG. 1 is a perspective view of divider of razor blade cartridge dispenser;

FIG. 2 is a front elevational view thereof;

FIG. 3 is a back elevational view thereof;

FIG. 4 is a right side elevational view thereof;

FIG. 5 is a left side elevational view thereof;

FIG. 6 is a top plan view thereof; and,

FIG. 7 is a bottom plan view thereof.

While the ornamental design for a divider is shown in the environment of a dispenser in which the design is repeated four times, the divider of the claimed ornamental design can be used as a single divider or with other numbers of dividers. The environment in which the design is used is a transparent dispenser. Other structures of the dispenser environment that are not shown on the drawings of this application, i.e., structures that can be seen through the walls of the dispenser, are shown in drawings of an application entitled "Razor Blade Cartridge Dispenser" which is being filed concurrently herewith; U.S. Ser. No. 29/067,307.
